US0D1039499S

(12) **United States Design Patent** (10) **Patent No.:** **US D1,039,499 S**
(45) **Date of Patent:** **** Aug. 20, 2024**

(54) **BATTERY PERFORMANCE MAINTENANCE DEVICE**

(71) Applicant: **CPS Technology Holdings LLC**, New York, NY (US)

(72) Inventors: **Daryl C. Brockman**, Shorewood, WI (US); **Timothy Corcoran Repp**, Barkhamsted, CT (US); **Gerald Jay Demirjian**, Auburn, NH (US); **Benjamin Craig Shaffer**, Bedford, NH (US); **Brian D'Amelio**, Auburn, NH (US); **Ximing He**, Boston, MA (US)

(73) Assignee: **CPS Technology Holdings LLC**, New York, NY (US)

(**) Term: **15 Years**

(21) Appl. No.: **29/858,388**

(22) Filed: **Oct. 31, 2022**

(51) LOC (14) Cl. **13-02**

(52) U.S. Cl.

(57) **CLAIM**

The ornamental design for a battery performance maintenance device, as shown.

DESCRIPTION

FIG. 1 is front perspective view of a battery performance maintenance device;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the drawings represent portions of the battery performance maintenance device that form no part of the claimed design.

1 Claim, 7 Drawing Sheets
